UNITED STATES PATENT OFFICE.

GEORGE IRVING DANLY, OF CHICAGO, ILLINOIS, ASSIGNOR TO DANLY MACHINE SPECIALTIES, INC., OF CHICAGO, ILLINOIS, A CORPORATION OF ILLINOIS.

FEEDING MECHANISM FOR GRINDING MACHINES.

Application filed July 25, 1927. Serial No. 208,356.

This invention relates to mechanisms for automatically feeding rollers, tappets and the like between the grinding and feeding wheels of the centerless type of roller grinding machines, and has for its various objects:

To provide a structural formation and association of parts in a feeding mechanism whereby the unfinished tappets or similar bodies are singly and successively taken from a loose mass of such bodies in a holding hopper, and placed in a row, one following the other upon a receiving track or table from which they are successively taken by a swinging carrier and deposited between the grinding and feeding wheels of a centerless grinding machine.

To provide means whereby the swinging carrier for the unfinished bodies, is automatically actuated in unison with the mechanism of a centerless grinding machine that expels the ground roll or like object from the machine, and so that said carrier in a position adjacent to the associated grinding and feeding wheels of the machine will have its work gripping means operated to a release position to drop an unfinished tappet or like piece of unfinished work between said wheels in unison with the action of the aforesaid expelling mechanism on a piece of work that has been finished.

To provide a structural formation and combination of parts in the swinging work carrier and its work engaging jaws, adapted to attain an initial opening and subsequent holding movement of grasping jaws of the carrier upon a piece of work, with a holding of said piece of work during the forward swing of the carrier to its proper delivery position, with an automatic release of the piece of work as such position is reached.

To provide means whereby the swinging carrier, at rest at its work delivery position, is automatically set in motion to move to its proper delivery point, and then have a return movement to its rearward work engaging position to engage a succeeding piece of work and a forward movement to the point of rest above set forth. Such forward movement of the swinging carrier following the rear movement of the same, after a slight period of rest during which the gripping jaws of the carrier engaged a piece of work.

To provide a structural formation and combination of parts whereby the gripping

jaws of the swinging carrier are automatically opened and closed upon a piece of work in one position of said carrier and at a succeeding period of such movement, said jaws are opened to deliver the piece of work to the grinding and feeding wheels of a grinding machine and in unison with the operation of said machine.

To provide means whereby the controlling means of the operating mechanism by which intermittent movement is imparted to the swinging work holder, is rendered certain in continued operating of the work feeding mechanism, all liability to interference due to a lack of full throw or movement of the tappet mechanisms by which the controlling mechanism aforesaid is actuated, is avoided in a certain and effective manner.

To provide a structural formation and combination of a supply hopper, a selecting appliance and a work receiver track or table, whereby the unfinished tappet or like piece of work is lifted in single order, and positioned on said track or table for engagement by the gripping jaws of a carrier by which the work is carried to and delivered to the wheels of a grinding machine or the like, all as will hereinafter more fully appear.

In the accompanying drawings:—

Fig. 1 is a side elevation of the preferred form of the present invention, and showing the same in associated relation to parts and portions of a centerless roll grinding machine.

Fig. 1^a is a fragmentary longitudinal section showing the primary power shaft and the countershaft operatively connected thereto.

Like reference numerals indicate like parts in the several views.

35 For the purpose of illustrating the operative association of the present automatic work feeding mechanism with a centerless roll grinding machine, the grinding wheel 1, associated feeding wheel 2, the rocker shaft 3 by which the finished work ejecting mechanism is operated and a portion 4 of the main frame of such grinding machine, is shown in Figs. 1 and 2.

40 The purpose of the present invention is to attain the feeding of cylindrical bodies, such as headed valve tappets having a cylindrical shank and an enlarged head at one end, in an automatic and serial manner to proper grinding relation between the grinding wheel 1 and associated feeding wheel 2 of a 45 centerless roll grinding machine of any usual and adaptable construction.

45 The preferred general arrangement of the present mechanisms as shown in Figs. 1 and 2 comprises a stationary supporting frame 60 or bed 5, fixedly attached to the main frame 4, of a grinding machine and provided with transverse guides 5' upon which is mounted in a transversely adjustable manner a hopper 6 for containing a supply of unground 65 tappets, or the like to be ground. The ob-

ject being to adjust the present feeding mechanism to proper relation with the grinding and feeding wheels of the grinding machine, from time to time, as said grinding wheel wears away in continued use. 70

The hopper 6 constitutes the support for the different units of the feeding mechanism, and is preferably of the rectangular form shown, with its bottom wall or floor sloping down from the four sides and formed with 75 a central longitudinal slot extending from one end to midway the length of the hopper, for the movement of an oscillating selector member 7 by which the unground tappets are lifted serially from the hopper 6 and 80 transferred unto a stationary receiving track or table 11, hereinafter described in detail.

85 The oscillating selector member 7 as shown in Figs. 1 and 3, comprises a pair of vertically arranged counterpart plates 8, segmental in shape, and attached at their lower ends to the opposite sides of a radial intermediate web 9, the carrying hub 9' of which is mounted on a transverse shaft 10, which in turn is journalled in bearings at an 90 end of the hopper 6, the construction providing for the required oscillatory movement of the selector member by an operating mechanism hereinafter described. In the present construction the aforesaid flat intermediate 95 web 9 is of a width somewhat greater than the diameter of the shank portion of the unground tappets to be operated on, in order that the shank portion of a tappet may freely enter the space between the spaced selector plates 8, in the operation of the mechanism and be lifted up by its headed portion and deposited on the stationary receiving track or table 11 now to be described. 100

105 The stationary receiving track or table 11 above referred to, comprises a pair of vertically arranged plate members fixedly attached to the hopper 6, in aligned relation to the selector plates 7 aforesaid, and in similarly spaced relation to provide a runway 110 for the shank portions of the unground tappets on the receiving track 11. Each of said plate members is formed with a horizontally arranged forward track portion 12 upon which the unground tappets are supported in position to be engaged by the gripping jaws of the swinging carrier hereinafter described, and extending rearwardly from said forward portions the said plates are formed with a rearward portion 13, in aligned and contact relation to the respective selector plates 7 and with the upper edges or faces of such rearward portion 13 having an upwardly inclined formation, corresponding with the inclination of the upper edges or faces of the selector plates 7 when in their fully elevated position so as to constitute a straight line extension thereof. 115

120 In the preferred construction shown in Figs. 1, and 3, the rear edges of the plate 130

members constituting the receiving track 11, is of a convex form for sliding contact of the concave forward edges of the selector plates 7, aforesaid.

With the described arrangement of parts, and with an unground tappet supported by its headed portion upon the upper edges of the selector plates 7 with its shank portion depending into the space or runway between the plates, said tappet will, as the selector plates nears their elevated position, slide by gravity in a downward direction onto and between the inclined rearward portion 13 of the stationary receiving track 11, and from thence to a position of rest upon the horizontal forward portion 12 of said track, for accurate positioning thereon by the hereinafter described automatic positioning mechanism, so as to be engaged by the gripping jaws of the hereinafter described swinging carrier by which the tappet is taken and carried and delivered to the grinding and feeding wheels 1, 2, of a grinding machine.

Accidental passage to and entry on the receiving track 11 above described of an unground tappet of a greater size than the size for which the mechanism is arranged and intended is automatically prevented by an association of parts as follows:—

A reciprocating head 14 of a rectangular shape and formed with side walls or flanges 15, is slidingly mounted on the upper edge or face of the track portion, 13, with the walls or flanges 15 in bearing contact with such edges of said track portions. The walls or flanges 15 are spaced apart a distance which permit passage of the headed portion of an unground tappet of the proper size, while preventing the passage of a tappet head or other body of a size greater than the space separating said walls or flanges 15, and so that in the normal reciprocation of the head 14, such irregular articles will be swept off the track portion 13, back into the hopper 6, for removal by the operator when he observes the same.

Motion of the reciprocating head 14 in unison with the movement of the selector plates 8, is attained by a rock arm 16 associated with said plates and having link connection 17 with the head 14, as shown in Fig. 1.

Intermittent oscillation of the selector member 7 aforesaid, is attained by means of a crank or wiper arm 18 carried by a transverse shaft 19 which has operative connection with the primary longitudinal driving shaft 20 of the machine through a worm and worm wheel connection 21 contained in a housing 21', by which the mechanism is protected from accident. In the construction shown said shaft 20 is supported in bearings on the hopper 6, and preferably receives motion from an operating motor 22, mounted on said hopper.

The crank or wiper arm 18 has operative contact with the forward and lower end of the selector member 7, which at such point of contact is formed with concave depressions 23 in which the crank or wiper arm 18 travels without imparting movement to the selector member 7, in order that said plates may have a period of rest in their fully elevated position.

With the present construction and arrangement of parts the normal position of the series of unground tappets in their downward passage along the inclined rear portion 13 of the receiving track or table 11 aforesaid, is with the fore portions of the heads of the rearward tappets resting or riding on the rear portions of the heads of the tappets at a point where the inclined rearward portion 13 of the trackway 11 joins the horizontal forward portion thereof, means as follows are provided:

Adjacent to the above stated point of juncture of the track portions 12 and 13, and at a distance above the same, slightly greater than the height of the head of an unground tappet for which the present mechanism is set or adjusted as shown in Fig. 6, a bridge rail 24 is fixedly supported, and with its rearward end formed with an upwardly and rearwardly inclined face 25. With such construction the head portion of the foremost unground tappet is free to pass beneath the bridge rail 24, while the head portion of the next rearward unground tappet is in contact with the inclined face 25 of said bridge rail, and held, along with the rest of the unground tappets, from any forward movement until the aforesaid foremost tappet of the series is engaged and moved forward from its above described position by the automatic positioning means now to be described.

Near the forward end of the horizontal portion 12 of the receiving track or table 11, a spring actuated holding block or jaw 26 is slidingly arranged at one side of the central runway of said track portion 12 and projecting into said runway. The side of the block or jaw 26 facing said runway is formed with a bevelled rear portion 27 and forward of the same with a V shape recess 27' as shown in Fig. 5, with the bevel portion 27 adapted for contact with the shank portion of a forwardly moving tappet to effect a retracting movement of the block or jaw, and so that in a final forward movement of said tappet to aligned relation with the V shape recess 27' of the holding jaw, the same will move under the influence of its spring into holding engagement with the shank of the tappet to yieldingly hold the tappet in proper position for engagement by the gripper head and mechanism of the swinging carrier hereinafter described.

Another and coacting portion of the posi-

tioning mechanism consists of a horizontally arranged hook bar 28, see Figs. 2 and 5, having longitudinal reciprocation in operative relation to an open side of the receiving track or table 11, and the series of unground tappets supported thereon. Reciprocating movement, in unison with the other units of the present structure, may be attained by any suitable means, preferably by a carrier head 10 or block 29 fixedly attached to the herein-after described reciprocating rack bar of the mechanism by which oscillation is imparted to the swinging carrier of the machine. In the construction shown in Figs. 2, 5 and 6, 15 the hook bar 28 is pivotally mounted at its forward end on the carrier head 29 and is yieldingly moved towards the trackway 11 by an interposed spring 28'. The rear and free ends of said bar 28 is formed with a 20 lateral hook or prong 30, of an approximately triangular shape. Associated with such rear end of the hook bar 28, is a spring 31, the tendency of which is to yieldingly force the hook or prong 30 towards the central runway of the receiving track or table 11 aforesaid, and between the foremost and next foremost of the series of unground tappets on said track or table, to thus attain 25 operative engagement with the shank of the foremost of said tappets, and operative contact with the shank of the next foremost tappet and force the same in a rearward direction from the heretofore described riding position of its head portion upon the 30 head portion of the foremost tappet to a position to subsequently replace the said foremost tappet.

In its forward stroke, the hook bar 28 carries the foremost tappet, above mentioned, along the receiving track or table 11 and central runway thereof and force the shank portion of such tappet into the heretofore described yielding engagement with the spring holding block or jaw 26 aforesaid.

The swinging carrier heretofore referred to, and by which the unfinished tappet is picked up from the holding block or jaw 26 aforesaid, by the headed portion of the 50 tappet, and carried to and delivered between the grinding wheel 1 and feeding wheel 2 of a centerless roll grinding machine, and as illustrated in Figs. 1, 2, 8, 11, 15 and 16 comprises an oscillatory crane arm 32 fixed at its lower end on a transverse tubular shaft 33, the housing 34 of which is fixedly attached to the rear of the hopper 6, with said housing containing the operating mechanism, herein-after described in detail, by 55 which an intermittent oscillatory movement, approximately 90°, in a vertical plane is imparted to said crane arm.

At its upper end the crane arm 32 is of a yoke form and provided with bearings in

which is journalled the journal hubs 35 of 65 the semi-rotary gripper head 36, now to be described.

In the preferred form shown in Figs. 1, 2, 15, 16 and 17, the gripper head 36 consists of two portions integrally connected in angular relation, with one portion forming the journal hub of the head and in turn providing a bearing for the herein-after described semi-rotary pinion shaft 37 by which the automatic opening and closing movements 70 of the gripping jaws of the gripper head are controlled. The other portion of the gripper head 36 is of a flat formation and is provided with bearings for the journal stems of a pair of movable gripping jaws 38, arranged in opposed relation to each other and to a fixed abutment jaw 39 on said portion of the gripper head 36.

The journal stems of the movable gripping jaws 38 are connected together by gear 85 wheels 40 in order that said jaws will move in unison in their opening and closing movements, with one of said gear wheels in operative engagement with the heretofore mentioned pinion shaft 37 as shown more particularly in Fig. 17, with said pinion 37 having operative engagement in turn with a toothed rack portion 41 of an operating stem 42 now to be described.

The operating stem 42, above referred to 95 is slidingly mounted in a tubular bore of the journal hubs 35 of the gripper head 36 aforesaid, and near one end is formed with the aforesaid toothed rack formation 41 of the operating means of the gripping jaws 38 100 aforesaid.

A yielding tendency of the operating stem 42 to move in one direction to maintain the gripping jaws 38 in their normally closed condition is attained by an associated spring 105 43, while a positive movement of the stem 42 in an opposite direction to effect an opening of the jaws 38 is attained through a lever 44, pivoted on a side of the crane arm 32, with one arm of the lever in operative 110 engagement with an end of the stem 42, and the other arm of the lever in operative engagement with a push rod 45, which in turn is operated by a tappet mechanism, herein-after described and by which the opening 115 movement of the gripping jaws 38, to at one time engage the head of an unground tappet on the receiving track or table 11 aforesaid, and at another and subsequent time open said jaws to release said tappet is automatically attained at proper intervals in the operation 120 of the present machine.

In the present invention, and during a normal swing of the carrier and its crane arm 32 aforesaid, the gripper head 36 receives an independent circular movement of 125 180°, with relation to the crane arm 32 with a view to attain a proper delivery position

of an unground tappet to the grinding machine by an arrangement of parts as follows:

A gear wheel 46 is fixedly connected with the gripper head 32 and is in operative engagement with a similar, but larger, sector gear wheel 47 journalled on the crane arm 32 and having an operating arm 48 which in turn has link connection 49 with a stationary part of the supporting structure.

With the described arrangement, the gripper head 32 will turn the above mentioned 180°, during the period it is carried it is being bodily carried 70° in the normal swing or oscillation of the crane arm 32 of the swinging carrier.

Proper intermittent operation of the swinging carrier and control of the automatic gripping mechanism of the same is attained by driving and controlling means as follows:

A longitudinally arranged countershaft, formed by two aligned sections 50 and 51, is journalled in bearings on a fixed portion of the structure as shown in Figs. 2 and 8, with the rearward shaft section 50 receiving constant rotation from the primary driving shaft 20, aforesaid, through an intermediate vertical shaft 52, having suitable gearing connections 20' and 50' with the aforesaid primary driving shaft 20, and rearward section 50 of the aforesaid countershaft section 50, as shown in Figs. 1^a, 7 and 8.

The aligned sections 50, 51 of the aforesaid countershaft are detachably coupled together by a clutch 53, the movable member 53' is actuated and controlled by means hereinafter described, and so that with the members of the clutch 53 in engagement the two shaft sections 50 and 51 will rotate in unison, while with said clutch members in a disengaged condition the forward shaft section 51 will come to a rest, while the rearward shaft section 50, will continue its rotation.

Undue rotation of the forward shaft section 51, due to momentum, when the members of the clutch 53 are released, is prevented by contact of the movable clutch member 53' with a friction cushion 54 arranged in the path of said clutch member, as illustrated in Fig. 8.

In the construction shown in Figs. 8, 9 and 10, the movable member 53' of the clutch 53 is operatively connected to a longitudinally arranged sliding bar 55 by which said movable clutch member is moved to its engaged and disengaged positions. The sliding bar 55 carries a pivoted dog or pawl 56 adapted to engage a fixed shoulder 57 of the structure to maintain the clutch members in their engaged condition, against the retracting tendency of a spring 58, arranged between the sliding bar 55, and a fixed part of the structure, with said engaged condition of the clutch members prevailing until the

pawl or dog 56 is moved to a release by the means hereinafter described.

The movement of the aforesaid sliding bar 55 to attain an engaged condition of the clutch 53, is effected at the proper period in the operation of the combined grinding and feeding mechanisms and by means as follows:

At its forward end the sliding bar 55, is formed with an inclined contact face 55', adapted for operative engagement with a complementary inclined contact face 59' of a vertically sliding bar 59, the lower end of which is arranged in the path of a rock arm 60, carried by the heretofore described rock shaft 3 of the ejector mechanism of the grinding machine, with said rock-arm adapted to move the vertical bar 59 upwards at the proper moment, to in turn impart a rearward movement to the sliding bar 55, to move the movable member 53' of the clutch 53 into its above mentioned engaged condition, in which engaged position it is held by an automatic engagement of the pawl or dog 56 with the fixed stop or shoulder 57, heretofore described.

Adjacent to its forward end the forward shaft section 51 carries a worm or screw 61 as shown in Fig. 10, that has operative engagement with a worm wheel 62, the carrying shaft 63 of which is revolvably mounted in the supporting housing 34 of the swinging carrier heretofore described, and with said shaft carrying the hereinafter described tappet and cam disk by which the release of the aforesaid clutch 53 and the serial opening and closing movements of the gripping jaws 38 of the swinging carrier aforesaid, are effected at the proper periods in the cycle of operations of the mechanism.

In adjacent relation to the free face of the worm wheel 62 aforesaid, a longitudinally sliding rack bar 64 is mounted and has operative engagement with the worm wheel 62, by a crank pin 65 on the worm wheel 62, working in vertically slotted head of yoke 66 on the rack bar 64, and commonly termed a "scotch yoke." The toothed portion of the rack bar 64 has operative engagement, in turn, with a gear wheel 67, mounted on the heretofore described tubular carrying shaft 33, of the crane arm 32 of the swinging carrier of the machine. The construction and arrangement of the parts is such that an oscillatory movement of 70° is imparted to the shaft 33 and crane arm 32 in the normal operation of the machine.

With a view to avoidance of accident, or breakage of parts due to accidental impedance in the normal movement of the crane arm 32 the aforesaid gear wheel 64 is loosely mounted on the shaft 33 and has yielding driving engagement with said shaft by a preferred construction as follows:

Fixedly attached to the shaft 33 is an

abutment collar 68, as shown in Fig. 14, and between said collar and the gear wheel 67 a sliding sleeve 69 is arranged and connected to said shaft by a key, and keyway connection 70 to positively rotate in unison with said shaft while having a sliding movement thereon.

The face of the sliding sleeve 69 adjacent to the gear wheel 63 is formed with one or 10 more recesses 71, the opposed walls of which have an inclined formation, and are adapted to engage complementary lugs or projections 72 on the side of the gear wheel 64 and provide an operative engagement between said 15 sleeve and said gear wheel in the normal operation of the mechanism. Intermediate of the sleeve 69 and the abutment collar 68, one or more compression springs 73 are arranged, and are adapted to yieldingly maintain 20 an operative engagement between the aforesaid recesses 71 and lugs 72 in the normal operation of the mechanism, and under excess stress permit movement of the lugs 72 out of operative engagement in the re- 25 cesses 71 aforesaid.

In the preferred construction shown in Figs. 8, 11 and 15, the before described push rod 45 by which the gripping jaws 38 of the gripper head 36 aforesaid are operated, extends 30 through and is guided in the central bore of the tubular carrying shaft 33 of the swinging carrier, with its end opposite to that engaging the operating lever 44 of the gripping jaws, adapted for operative engagement by the controlling mechanism now to be described.

The carrying shaft 63 of the worm wheel 62 extends outside the enclosing casing 34, and carries a rotary disk 74 upon which are 40 attached operating lugs as follows:

A single lug or tappet 75 is secured to the periphery of the rotary disk 74, and has movement in a path in which a projecting portion or toe of the heretofore described 45 pawl or dog 56 of the clutch actuating mechanism extends, and so that as said lug 75 reaches operative engagement with said projecting portion or toe of the holding pawl or dog 56 the same will be pushed out 50 of holding engagement with the aforesaid stop shoulder 57 permitting the spring 58 to move the clutch 53 into an open or disengaged condition.

In addition to the lug or tappet 75 above 55 described, a pair of cams or tappets 76, 77, are secured in circular spaced relation in an adjustable manner on the rotary disk 74 aforesaid, and in a path outside the path of the single tappet 75 aforesaid. The cams 60 or tappets 76, 77, are adapted for serial operative engagement with one end of a rock lever 78, the other end of which has operative engagement with an adjacent end of the heretofore described push rod 45. The ar- 65 rangement of the parts is such that with the

gripper head 36 of the crane arm 32 of the swinging work carrier, in a position to pick up and carry an unground tappet, the gripping jaws 38 will be caused to open by the foremost tappet 76 to engage the head of 70 the unground tappet and then released to close upon and grip said head. In like manner, as said gripper head 36, holding an unground tappet, reaches a position in which the unground tappet is to be deposited between the grinding wheel 1 and feeding wheel 2 of the centerless grinding machine, the other tappet 77 will come into action to cause the gripping jaws 38 to open and release the unground tappet which then descends by gravity between the aforesaid 75 grinding and feeding wheels 1 and 2.

With a view to the prevention of accidental stoppage of the mechanisms above described by a premature stoppage of the lug 85 or tappet 75, in aligned relation with the respective operating projection of the holding pawl or dog 56, a construction of parts as follows is provided:

The central and main portion of the rotary disk 74 aforesaid is fixed on its carrying shaft 63 and has an annular rim portion or ring 79, loosely mounted on its periphery so as to be capable of independent turning movement, with such turning movement of 90 the rim portion limited in extent by a lug 80 on one part moving in an elongated slot 81 in the other portion, while a normal forward position of the ring is yieldingly maintained by an intermediate compression 95 spring 82. In such construction the aforesaid lug or tappet 75, is carried by the ring or annular portion 79, and as said lug or tappet reaches an operative position, the stress or resistance met with effects a compression of the spring 82 until the lug 80 of the hub portion of the rotary disk 74 reaches the forward end of the elongated slot 81 of the ring or annular portion 79, at 100 which point positive revolution of the parts 105 takes place with positive action on the part of the said lug or tappet.

With the crest of said lug or tappet 75, reaching the contact point of the pawl 56 which it operates, the stored energy of the spring 82 acts to return the annular portion or ring 79 to its normal position above described, and carry the lug or tappet 75 a distance beyond such point of operative contact, thus preventing any stalling of the mechanism due to the crest of the lug or tappet 75, coming to a rest or stop in aligned relation to the point of contact with the holding pawl it is adapted to operate.

The operation of the present mechanism 115 in general is as follows:

With the present feeding mechanism in the position of parts illustrated in Figs. 1 and 2, with the swinging work carrier 32 and its gripper head 36 in a position adja- 120 130

cent to the grinding wheel 1 and feeding wheel 2, of a centerless roll grinding machine, said gripper head, holding by its gripping jaws 38, 38 and 39, an unground tappet 5 in proper position for delivery. The mechanisms and parts being at rest in the described position, the subsequent automatic operation of such mechanisms and parts is as follows:

10 As the rock shaft 3, receives a rocking movement in the operation of ejecting a ground tappet as it passes down from between the grinding and feeding wheels 1 and 2, of a centerless grinding machine, the rock 15 arm 60, on said rock shaft 3 has engagement with the vertically sliding bar 59, to move the same upwards, and in turn impart rearward longitudinal movement to the sliding bar 55, through the inclined contact faces 20 55' and 59' of said parts.

With longitudinal rearward movement of the sliding bar 55, the movable clutch member 53' is moved into engagement with the stationary member of the clutch 53 to cause 25 rotation of the countershaft section 51, to in turn impart rotation and movement to the automatic mechanisms of the present structure.

During the described longitudinal rearward movement of the sliding bar 55 its holding dog or pawl 56 comes into engagement with the fixed shoulder or stop 57, to lock the sliding bar 55 in its rearward position, against the retractile tendency of the 35 spring 58, with the aforesaid clutch members in engagement. The rotation of the countershaft section 51 thus attained, is imparted by the heretofore described intermediate gearing and connections to the 40 swinging work carrier 32, to cause the same to complete its forward swinging movement, at or about which point, the cam or tappet 76 acting against the rock lever 78, imparts transverse movement to the push rod 45, 45 which in turn and through the lever 44 operating stem 42, and gearing connections 41, 37 and 40 acts to impart an opening movement to the gripping jaws 38, to release an unground tappet, held therebetween, so that 50 such tappet will fall by gravity between the grinding and feeding wheels 1 and 2 of the grinding machine.

With such delivery of an unground tappet attained, the swinging work carrier 32 then 55 continues and completes a rearward swinging movement, to bring the gripper head 36 and gripping jaws 38, 38, 39, into proper position to grip an unground tappet held in the spring holding block or jaw 26, at which 60 stage in the movement of the carrier 32, the cam or tappet 77 acts through the aforesaid lever 78, push rod 45, lever 44, stem 42 and gearing connections 41, 37 and 40, to impart an opening movement to the gripping 65 jaws 38 aforesaid, to engage an unground

tappet in the aforesaid holding block or jaw 26, and then permit said gripping jaws 38 to close upon and hold said unground tappet, under the normal tendency of said jaws to a closed position, when not held open positively.

With the completion of the described rearward swinging movement of the work carrier 32, the same begins a forward swinging movement and continues the same until 70 it reaches the position first above described in the cycle of operations of the mechanisms, and as it reaches such position the cam or tappet 75 contacts with the holding dog or pawl 56, to release the same from holding engagement with the fixed shoulder or stop 57, and permit the spring 58, to impart a forward movement to the sliding bar 55, thereby moving the movable clutch member 53' to its disengaged position, to cause 80 a stoppage of the aforesaid mechanisms, until the rock shaft 3 of the ejector mechanism of the associated grinding machine starts up a fresh cycle of the movements above described.

Having thus fully described my invention, what I claim and desire to secure by Letters Patent, is:—

1. In an automatic feeding mechanism of the type described, the combination of a work supporting track or table for the articles to be finished, a swinging carrier in operative relation to said track and having at its free end a work gripping means, means for imparting a swinging movement to the carrier to and from said supporting track, means actuated by mechanism of an associated finishing machine for starting the carrier operating means in action, the said carrier operating means including means for automatically stopping the operating means of the carrier when the carrier is in adjacent relation to finishing means of an associated finishing machine, means for automatically opening and closing the work gripping means of the carrier, when said carrier is in a position adjacent to the supporting track, and means for opening said gripping means when the carrier is in close relation to said finishing means of an associated finishing machine.

2. In an automatic feeding mechanism of the type described the combination of a work supporting track or table for the articles to be finished, a swinging carrier in operative relation to said track and having at its free end work gripping means, means for imparting a swinging movement to the carrier to and from said supporting track, the same comprising a driving countershaft, an intermittent driven shaft, a clutch connection between said shafts, intermittently acting means for moving said clutch to its active condition, a spring acting to move said clutch to an inactive condition, a pawl 120 125 130

adapted to hold said clutch in its active condition, a rotary cam disk operatively connected to said driven shaft and carrying a cam lug or tappet adapted to move the afore-
5 said pawl to a release condition, operative connections between the carrying shafts of the aforesaid cam disk and swinging carrier for imparting movement to said carrier and means operating in unison with said cam
10 disk for effecting a periodical opening and closing of the gripping means of the carrier.

3. In an automatic feeding mechanism of the type described the combination of a work supporting track or table for the articles to be finished, a swinging carrier in operative relation to said track and having at its free end a work gripping means, means for imparting a swinging movement to the carrier to and from said supporting track, the same 15 comprising a driving countershaft, an intermittent driven shaft, a clutch connection between said shafts, intermittently acting means for moving said clutch to its active condition, a spring acting to move said clutch
20 to an inactive condition, a pawl adapted to hold said clutch in its active condition, a rotary cam disk operatively connected to said driven shaft and carrying a resiliently mounted cam lug or tappet adapted to move
25 the aforesaid pawl to a release condition, operative connections between the carrying shaft of the aforesaid cam disk and swinging carrier for imparting movement to said carrier, and means operating in unison with said
30 cam disk for effecting periodical opening and closing of the gripping means of said carrier.

4. In an automatic feeding mechanism of the type described the combination of a work supporting track or table for the articles to be finished, a swinging carrier in operative relation to said track and having at its free end a work gripping means, means for imparting a swinging movement to the carrier to and from said supporting track, the same 40 comprising a driving countershaft, an intermittent driven shaft, a clutch connection between said shafts, a sliding bar connected to the movable element of said clutch and receiving intermittent movement from an associated finishing machine to move the clutch to its active condition, a spring acting to move said clutch to an inactive condition, a pawl adapted to hold said clutch in its active condition, a rotary cam disk operatively connected to said driven shaft and carrying a cam lug or tappet adapted to move the afore-
45 said pawl to a release condition, operative connections between the carrying shafts of the aforesaid cam disk and swinging carrier for imparting movement to said carrier, the same comprising a crank pin on said cam disk, a sliding rack bar having a yoke member engaging said crank pin, and a gear wheel on the carrying shaft of the swinging carrier having operative engagement with said rack bar, and means operating in unison with said cam disk for effecting a periodic opening and closing of the gripping means of the carrier.

55 5. In an automatic feeding mechanism of the type described, the combination of a work supporting track or table for the articles to be finished, a swinging carrier in operative relation to said track and having at its free end a work gripping means, means for im-
60 for imparting movement to said carrier, and means operating in unison with said cam disk for effecting a periodical opening and closing of the gripping means of the carrier.

65 6. In an automatic feeding mechanism of the type described, the combination of a work supporting track or table for the articles to be finished, a swinging carrier in operative relation to said track and having at its free end a work gripping means, means for im-

work supporting track or table for the articles to be finished, a swinging carrier in operative relation to said track and having at its free end a work gripping means, means for imparting a swinging movement to the carrier to and from said supporting track, the same comprising a driving countershaft, an intermittent driven shaft, a clutch connection between said shafts, intermittently acting means for moving said clutch to its active condition, the same comprising a rock arm moving in unison with an element of an associated finishing machine and having operative connection with the movable element of said clutch, a spring active to move said clutch to an inactive condition, a pawl adapted to hold said clutch in its active condition, a rotary cam disk operatively connected to said driven shaft and carrying a cam lug or tappet adapted to move the aforesaid 75 pawl to a release condition, operative connection between the carrying shafts of the aforesaid cam disk and swinging carrier for imparting movement to said carrier, and means operating in unison with said cam disk 80 for effecting a periodical opening and closing of the gripping means of the carrier.

6. In an automatic feeding mechanism of the type described, the combination of a work supporting track or table for the articles to be finished, a swinging carrier in operative relation to said track and having at its free end a work-gripping means, means for imparting a swinging movement to the carrier to and from said supporting track, the same 95 comprising a driving countershaft, an intermittent driven shaft, a clutch connection between said shafts, intermittently acting means for moving said clutch to its active condition, a spring acting to move said clutch to an inactive condition, a pawl adapted to hold said clutch in its active condition, a rotary cam disk operatively connected to said driven shaft and carrying a cam lug or tappet adapted to move the aforesaid pawl to a release condition, operative connections between the carrying shafts of the aforesaid cam disk and swinging carrier for imparting movement to said carrier, the same comprising a crank pin on said cam disk, a sliding rack bar having a yoke member engaging said crank pin, and a gear wheel on the carrying shaft of the swinging carrier having operative engagement with said rack bar, and means operating in unison with said cam disk for effecting a periodic opening and closing of the gripping means of the carrier.

7. In an automatic feeding mechanism of the type described the combination of a work supporting track or table for the articles to be finished, a swinging carrier in operative relation to said track and having at its free end a work gripping means, means for im-

to and from said supporting track, the same comprising a driving countershaft, an intermittent driven shaft, a clutch connection between said shafts, intermittently acting means for moving said clutch to its active condition, a spring acting to move said clutch to an inactive condition, a pawl adapted to hold said clutch in its active condition, a rotary cam disk operatively connected to said driven shaft and carrying a cam lug or tappet adapted to move the aforesaid pawl to a release condition, operative connections between the carrying shafts of the aforesaid cam disk and swinging carrier for imparting movement to said carrier, the same comprising a crank pin on said cam disk, a sliding rack bar having a yoke member engaging said crank pin, and a gear wheel on the carrying shaft of the swinging carrier having operative engagement with said rack bar, said gear wheel having yielding operative connection with the carrying shaft of the swinging carrier, and means operating in unison with said cam disk for effecting a periodic opening and closing of the gripping means of the carrier.

8. In an automatic feeding mechanism of the type described, the combination of a receiving track for the articles to be finished, a swinging carrier in operative relation to said trackway, the same comprising a crane arm, a plurality of gripper jaws carried at the free end of the crane arm, means for normally holding said jaws in a closed condition, means for imparting intermittent oscillation to said crane arm with the same having periods of rest near the ends of its forward and backward swing, automatic means for effecting a temporary opening movement of said jaws for engagement with an article to be carried as said crane arm nears its rearward stroke, and for effecting a like opening movement of said jaws as the crane arm nears its forward stroke.

45 9. In an automatic feeding mechanism of the type described the combination of a receiving track for the articles to be finished, a swinging carrier in operative relation to said trackway, the same comprising a crane arm, a plurality of gripper jaws carried at the free end of the crane arm, means for normally holding said jaws in a closed condition, means for imparting intermittent oscillation to said crane arm with the same having periods of rest near the ends of its forward and backward swing, automatic means for effecting a temporary opening movement of said jaws for engagement with an article to be carried as said crane arm nears its rearward stroke, and for effecting a like opening movement of said jaws as the crane arm nears its forward stroke, the same comprising a rotary cam disk receiving motion from the operating mechanism of the crane arm and carrying a pair of circularly spaced tappets,

and intermediate operative connections between said tappets and the aforesaid plurality of gripper jaws.

10. In an automatic feeding mechanism of the type described the combination of a receiving track for the articles to be finished, a swinging carrier in operative relation to said trackway, the same comprising a crane arm, a semi-rotary head mounted on the free end of said crane arm, a plurality of gripper jaws mounted on said head, means for normally holding said jaws in a closed condition, means for imparting intermittent oscillation to said crane arm, means for effecting temporary opening movement to said jaws near the end of the forward and rearward stroke of said crane arm and means for imparting semi-rotation to the aforesaid during the swinging movements of the crane arm.

11. In an automatic feeding mechanism of the type described the combination of a receiving track for the articles to be finished, a swinging carrier in operative relation to said trackway, the same comprising a crane arm, a semi-rotary head mounted on the free end of said crane arm, a plurality of gripper jaws mounted on said head, means for normally holding said jaws in a closed condition, means for imparting intermittent oscillation to said crane arm, means for effecting temporary opening movement to said jaws near the end of the forward and rearward stroke of said crane arm and means for imparting semi-rotation to the aforesaid during the swinging movements of the crane arm, the same comprising a gear wheel fixed on said semi-rotary head, a sector gear journaled on the crane arm and having operative engagement with said gear wheel, and a connecting link having eccentric pivotal connection at one end with said sector gear wheel and at its other end pivotal attachment to a stationary part of the structure.

12. In an automatic feeding mechanism of the type described, the combination of a receiving track for the articles to be finished, a swinging carrier in operative relation to said trackway, the same comprising a crane arm, a semi-rotary head mounted on the free end of said crane arm, a fixed gripper jaws and a companion pair of pivoted gripper jaws mounted on said semi-rotary head, a transversely moving rack bar having operative connections with the hub portions of the pair of pivoted gripper jaws, means for imparting reciprocation to said rack bar, the same comprising a lever pivoted in the crane arm with one end bearing against said rack bar, a rotary cam disk moving in unison with the operating mechanism of the crane arm and carrying a pair of tappets in circular spaced relation, a rocking lever arranged for serial operation by said tappets and a transverse rod having operative connection at one end with said rocking lever

and at the other end with the aforesaid lever carried by the crane arm.

13. In an automatic feeding mechanism of the type described the combination of a receiving track for the articles to be finished, a swinging carrier in operative relation to said trackway, the same comprising a crane arm, a semi-rotary head mounted on the free end of said crane arm, a fixed gripper jaws and a companion pair of pivoted gripper jaws mounted on said semi-rotary head, a transversely moving rack bar having operative connections with the hub portions of the pair of pivoted gripper jaws, a spring for imparting movement to said rack bar in one direction, means for imparting positive movement to the rack bar in the opposite direction, the same comprising a lever pivoted on the crane arm with one end bearing against said rack bar, a rotary cam disk moving in unison with the operating mechanism of the crane arm and carrying a pair of tappets in circular spaced relation, a rocking lever arranged for serial operation by said tappets, and a transverse rod having operative connection at one end with said rocking lever and at the other end with the aforesaid lever carried by the crane arm.

14. In an automatic feeding mechanism of the type described, the combination of a receiving track for the articles to be finished, a swinging carrier in operative relation to said trackway, the same comprising a crane arm, a semi-rotary head mounted on the free end of said crane arm, a fixed gripper jaws and a companion pair of pivoted gripper jaws mounted on said semi-rotary head, a transversely moving rack bar having operative connections with gear formations on the hub portions of the aforesaid pivoted gripper jaws through intermediate gearing members, means for imparting reciprocation to said rack bar, the same comprising a lever pivoted on the crane arm with one end bearing against said rack bar, a rotary cam disk moving in unison with operating mechanism of the crane arm and carrying a pair of tappets in circular spaced relation, a rocking lever arranged for serial operation by said tappets, and a transverse rod having operative connection at one end with said rocking lever and at the other end with the aforesaid lever carried by the crane arm.

15. In an automatic feeding mechanism of the type described a positioning means for the articles to be finished, the same comprising a trackway formed by a pair of rails in spaced relation and formed with a horizontal forward portion and a rearward upwardly inclined portion, a spring actuated holding block arranged at one side of the forward portion of the trackway, and a pivotally mounted hook bar moving along said horizontal trackway portion and receiving intermittent reciprocation from the

operating mechanism of an associated carrier to serially and individually feed the unfinished articles to the aforesaid holding block.

16. In an automatic feeding mechanism of the type described a positioning means for the articles to be finished, the same comprising a trackway formed by a pair of rails in spaced relation and formed with a horizontal forward portion and a rearward upwardly inclined portion, a spring actuated holding block arranged at one side of the forward portion of the trackway, and a pivotally mounted hook bar moving along said horizontal trackway portion and receiving intermittent reciprocation from the operating mechanism of an associated carrier to serially and individually feed the unfinished articles to the aforesaid holding block, the free end of said hook bar having an approximately triangular shape adapted to effect a separation of the forward pair of articles on the trackway and a spring engaging said hook bar end to guide said end between a pair of the articles in the rearward movement of the hook bar.

17. In an automatic feeding mechanism of the type described, a positioning means for the articles to be finished, the same comprising a trackway formed by a pair of rails in spaced relation and formed with a horizontal forward portion and a rearward upwardly inclined portion, a spring actuated holding block arranged at one side of the forward portion of the trackway, a bridge rail having a rearwardly inclined face arranged above the trackway adjacent to the point of intersection of the horizontal and inclined portions of the trackway, and adapted to effect a rearward separation of the articles on the trackway in their forward travel thereon, and a pivotally mounted hook bar moving along said horizontal trackway portion and receiving intermittent reciprocation from the operating mechanism of an associated carrier to serially and individually feed the articles to the aforesaid holding block.

18. In an automatic feeding mechanism of the type described, the combination of a holding hopper formed with a longitudinal slot extending from the mid-length to one end of the hopper, a receiving track having aligned relation to said slot, an oscillatory selector member of a segmental form having movement in said slot and adapted to register with said receiving track, and means for imparting oscillatory movement to said selector member.

19. In an automatic feeding mechanism of the type described, the combination of a holding hopper formed with a longitudinal slot extending from the mid-length to one end of the hopper, a receiving track having an inclined portion in aligned relation with

- said slot, an oscillatory selector member of a segmental form having movement in said slot and adapted to register with said inclined portion of the receiving track, and 5 means for imparting an oscillatory movement to said selector member.
20. In an automatic feeding mechanism of the type described, the combination of a holding hopper formed with a longitudinal 10 slot extending from the mid-length to one end of the hopper, a receiving track having aligned relation to said slot, an oscillatory selector member comprising a pair of segmental plates secured together in spaced relation and having movement in said slot with their upper edges adapted to register with said receiving track, and means for imparting an oscillatory movement to said selector member.
- 20 21. In an automatic feeding mechanism of the type described, the combination of a holding hopper formed with a longitudinal 15 slot extending from the mid-length to one end of the hopper, a receiving track having an inclined portion in aligned relation with said slot, an oscillatory selector member comprising a pair of segmental plates secured together in spaced relation and having movement in said slot with their upper edges 20 adapted to register with said receiving track, and means for imparting an oscillatory movement to said selector member.
22. In an automatic feeding mechanism of the type described, the combination of a holding hopper formed with a longitudinal 25 slot extending from the mid-length to one end of the hopper, a receiving track comprising a pair of rails secured together in spaced relation and in alignment with said slot, an oscillatory selector member comprising a pair of segmental plates secured together in spaced relation and having movement in said slot with their upper edges 30 adapted to register with the receiving track, and means for imparting oscillatory movement to said selector member.
23. In an automatic feeding mechanism of the type described, the combination of a holding hopper formed with a longitudinal 35 slot extending from the mid-length to one end of the hopper, a receiving track comprising a pair of rails secured together in spaced relation and having upwardly inclined end portions, an oscillatory selector 40 member of a segmental form having move- 45 ment in said slot and adapted to register with said inclined portion of the track, and means for imparting oscillatory movement to said selector member.
24. In an automatic feeding mechanism of the type described, the combination of a holding hopper formed with a longitudinal slot 50 extending from the mid-length to one end of the hopper, a receiving track comprising a pair of rails secured together in spaced relation and in alignment with said slot, an oscillatory selector member of a segmental form having movement in said slot and adapted to register with said receiving track, means for imparting oscillatory movement to said selector member, a reciprocating clearer head moving on the receiving track, and operative connection between said clearer head and the oscillatory selector 55 member.
25. In an automatic feeding mechanism of the type described, the combination of a holding hopper formed with a longitudinal slot 60 extending from the mid-length to one end of the hopper, a receiving track comprising a pair of rails secured together in spaced relation and in alignment with said slot, an oscillatory selector member of a segmental form having movement in said slot and adapted to register with said receiving track, means for imparting oscillatory movement to said selector member, a reciprocating clearer head formed with a top web and side flanges in spaced relation and having movement on the receiving track, and operative 65 connections between said clearer head and the oscillatory selector member.
26. In an automatic feeding mechanism of the type described, the combination of a holding hopper formed with a longitudinal slot 70 extending from the mid-length to one end of the hopper, a receiving track comprising a pair of rails secured together in spaced relation and in alignment with said slot, an oscillatory selector member of a segmental form having movement in said slot and adapted to register with said receiving track, means for imparting oscillatory movement to said selector member, a reciprocating clearer head formed with a top web and side flanges in spaced relation and having movement on the receiving track, and operative 75 connections between said clearer head and the oscillatory selector member.
27. In an automatic feeding mechanism of the type described, the combination of a holding hopper formed with a longitudinal slot 80 extending from the mid-length to one end of the hopper, a receiving track comprising a pair of rails secured together in spaced relation and in alignment with said slot, an oscillatory selector member of a segmental form having movement in said slot and adapted to register with said receiving track, means for imparting oscillatory movement to said selector member, a reciprocating clearer head formed with a top web and side flanges in spaced relation and having movement on the receiving track, and operative 85 connections between said clearer head and the oscillatory selector member.
28. In an automatic feeding mechanism of the type described, the combination of a holding hopper formed with a longitudinal slot 90 extending from the mid-length to one end of the hopper, a receiving track comprising a pair of rails secured together in spaced relation and in alignment with said slot, an oscillatory selector member of a segmental form having movement in said slot and adapted to register with said receiving track, means for imparting oscillatory movement to said selector member, the same comprising a vibratory arm on the selector 95 member, and a link connecting said arm to the clearer head.

In testimony whereof I affix my signature.

GEORGE IRVING DANLY.
